CLAIM

The ornamental design for an electronic cigarette, as shown and described.

DESCRIPTION

FIG. 1 is a perspective view of the front, top, and right side of the design for an electronic cigarette;
FIG. 2 is a front plan view thereof;
FIG. 3 is a back plan view thereof;
FIG. 4 is a left side view thereof;
FIG. 5 is a right side view thereof;
FIG. 6 is a top plan view thereof;
FIG. 7 is a bottom plan view thereof;
FIG. 8 is a perspective view of the back, bottom, and left side thereof;
FIG. 9 is a perspective view of the front, top, and right side of the design for an electronic cigarette according to another embodiment;
FIG. 10 is a front plan view thereof;
FIG. 11 is a back plan view thereof;
FIG. 12 is a left side view thereof;
FIG. 13 is a right side view thereof;
FIG. 14 is a top plan view thereof;
FIG. 15 is a bottom plan view thereof; and,
FIG. 16 is a perspective view of the back, bottom, and left side thereof.
Any broken lines in the drawings depict disclaimed subject matter and form no part of the claimed design.

1 Claim, 14 Drawing Sheets
